GRINDER FOR PREPARING THIN SECTIONS OF
ROCKS, CERAMICS, FOSSILS AND THE LIKE

William F. Ingram, % Ingram Laboratories, Griffin, Ga.

Filed Oct. 2, 1962, Ser. No. 71,965

Term of patent 14 years

(Cl. D37—1)

Fig. 1

Fig. 2

Fig. 3

Fig. 4

Fig. 5

Fig. 6

FIG. 1 is a front elevational view of the grinder for preparing thin sections of rocks, ceramics, fossils and the like, embodying my new design;

FIG. 2 is a rear elevational view thereof;

FIG. 3 is a side elevational view taken from the left of FIG. 1;

FIG. 4 is a side elevational view taken from the right thereof;

FIG. 5 is a top plan view; and,

FIG. 6 is a right front perspective view thereof.

I claim:

The ornamental design for a grinder for preparing thin sections of rocks, ceramics, fossils and the like, as shown.
